GUIDE FOR T-SQUARE

Emil Baerwalde, Cleveland, Ohio

Application February 3, 1934, Serial No. 709,617

1 Claim. (Cl. 33—80)

This invention relates to an improved form of clamping attachment for a T-square for use in maintaining the T-square in proper position upon the drawing board.

5 I realize that there have already been patented numerous other devices for the same general purpose, but the object of my invention is to devise such an attachment that can be laterally applied to and removed from the side edge portion of the T-square in a convenient and quick manner.

Another object is to devise such an attachment that can be employed upon a conventional form of T-square without requiring any modification of either the T-square or the drawing board.

15 Other objects will be apparent from the following description and claim when considered together with the accompanying drawing.

Fig. 1 is a plan view of a T-square applied to a drawing board and equipped with one form of my attachment;

Fig. 2 is a view taken on line 2—2 of Fig. 1;

Fig. 3 is a view taken on line 3—3 of Fig. 2;

Fig. 4 is an inverted plan view of a modified form of attachment;

25 Fig. 5 is a front elevation of another modification; and

Fig. 6 is a side elevation of the modification shown in Fig. 5.

Referring to the accompanying drawing, my improved attachment, in all of its several forms, 30 comprises a base portion 1, an intermediate portion 2 extending upwardly from the rear thereof, and an upper portion 3 which joins the intermediate portion and over-lies the base portion in substantially parallel relation thereto. The upper portion 3 is free or unattached at its one end, 35 so as to permit the side edge portion of the T-square blade A to be received between the base and upper portions of the attachment. That is, and upper portions of the attachment. That is, 40 my attachment is applied laterally to the side edge portion of the T-square blade A by engaging the open front part thereof to the same so as to cause the intermediate portion 2 to engage the edge of the T-square blade A.

45 Mounted in the upper portion 3 is the screw clamp 4 which is adapted to clamp the T-square blade A against the base portion 1, as soon as the attachment has been placed in position. It will be understood that my attachment will be applied to the T-square blade A at the proper point thereof so as to clamp the same against the side edge of the drawing board C after the T-square has been placed thereupon, with the head B of the T-square engaging the opposite edge of the drawing board. The means for

clamping the drawing board will now be described.

The under side of the base portion 1, (Figs. 1, 2 and 3) is provided with two parallel cylinders 5 through which extend the plungers 6 and which house the coil springs 7 therefor. Upon the plungers 6 there is mounted the presser foot 8 which is adapted to engage the side edge of the drawing board. The springs 7 normally force the plungers 6 outwardly and the plunger rods 10 are provided at their opposite ends with the stop collars 9 which limit such outward movement of the plungers 6. When the attachment is applied to the T-square, it is placed in such position that the presser foot 8 will bear against the edge of the drawing board with the proper degree of pressure so as to maintain the T-square in any set position and yet permit the same to be readily moved up and down the drawing board.

The modified form of device illustrated in Fig. 20 4 is similar to that in Figs. 1, 2 and 3, except that there is provided only one plunger 5^a and a correspondingly smaller presser foot 8^a.

The form of device indicated in Figs. 5 and 6 is the same as that in Fig. 4 except that a roller 25 10 is mounted in a bracket 11 on the end of the plunger instead of the flat presser foot. The roller 10 is intended to engage the edge of the drawing board in a manner similar to the flat presser foot 8 in the other form of device. 30

If so desired, any suitable material, such as fabric or the like, might be applied to those faces which clamp the blade of the T-square, as indicated in the drawing.

It will be observed that the entire main body 35 of my device is formed as a single part, as may be done by casting the same out of light metal.

Also, my device is entirely open at the front thereof and thus can be applied laterally to the side edge portion of the T-square blade. It can 40 also be removed with equal facility.

Furthermore, my attachment does not involve any modifications in the T-square or in the drawing board.

Finally, this device can be manufactured and 45 sold at a comparatively low price.

What I claim is:

A holding attachment for a T-square, comprising a bracket having a base portion adapted to engage the under side of the T-square, an intermediate portion extending upwardly from only the rear of said base portion, and an upper portion extending from said intermediate portion and overlying said base portion, a clamping means extending through said upper portion 50 55

and adapted to clamp the T-square against the base portion, and spring-pressed plunger means mounted upon the under side of said base portion and having means for engaging the side edge of the drawing board to which the T-square is applied, said parts being so constructed and arranged that the bracket is entirely open except

for said intermediate portion so that the attachment can be applied laterally from the side thereof to the side edge portion of the T-square so as to receive the one edge of the T-square against the said intermediate portion of the attachment. 5

EMIL BAERWALDE.
